ABSTRACT OF THE DISCLOSURE

A method of controlling diarrhea by administering a therapeutically effective amount of 5,5-dimethyl-10-hydroxy - 8 - (3 - methyl-2-octyl)-2-(2-propynyl)-1,2,3,4-tetrahydro-5H-[1]benzopyrano[3,4-d]pyridine to a patient in need of such treatment.

DETAILED DESCRIPTION OF THE INVENTION

This invention relates to a method of controlling diarrhea using 5,5 - dimethyl - 10-hydroxy-8-(3-methyl-2-octyl) - 2-(2-propynyl) - 1,2,3,4-tetrahydro-5H-[1]benzopyrano[3,4-d]pyridine as the anti-diarrheal agent.

Morphine is one of the most potent agents known for controlling intestinal motility. However, morphine has two disadvantages; morphine is not active when administered orally and it is addicting. Therefore, while a single dose of morphine may be administered to stop severe episodes of diarrhea, it is generally not the drug of choice. Paragoric is also used for the control of diarrhea; however, because of its narcotic liability, it cannot be used for chronic administration.

While there are a number of currently available therapeutic agents which are useful in the treatment of acute episodes of diarrhea and with chronic episodes associated with colitis and the like, the search for improved agents with fewer side effects continues. The present invention provides one such agent.

5,5 - dimethyl - 10 - hydroxy-8-(3-methyl-2-octyl) - 2-(2 - propynyl) - 1,2,3,4 - tetrahydro - 5H - [1]benzopyrano[3,4-d]pyridine has previously been reported to be useful as a central nervous system depressant (see U.S. Pat. No. 3,576,798). It has now been found that the compound is useful as an anti-diarrheal agent.

The compound useful in the practice of this invention is represented by the formula

The compound can be prepared according to the method taught in U.S. Pat. No. 3,576,798.

In the practice of this invention, oral dosages of from 0.005 to 10 mg./kg. of body weight daily is administered to patients suffering from diarrhea or excessive intestinal motility. While a single dose of the drug can be administered to such patients, it is preferred to administer the drug in divided dosages, i.e., there to four times daily. While the oral route is preferred, the compound is also active by the intraperitoneal and can be administered via the intravenous or other injectable routes.

The following examples further illustrate this invention.

2

Example 1.—Oral effects of 5,5-dimethyl-10-hydroxy-8-(3 - methyl - 2-octyl)-2-(2-propynyl)-1,2,3,4-tetrahydro-5H - [1]benzopyrano[3,4 - d]pyridine on intestinal motility in mice

- 5 Group of 10 female Swiss-Webster (Wisconsin) mice weighing 16-24 g. were fasted overnight and then given various oral doses of the compound 0 to 60 minutes prior to a charcoal "meal." The compound was prepared as 0.00001 to 1% suspension in 0.5% methylcellulose. 10 Through the use of serial dilutions from the 1% suspension, it was possible to maintain the maximum volume given at 10 cc./kg. The charcoal (Norit) was prepared as a 5% suspension in 0.5% methylcellulose and administered at a volume of 0.25 cc. per mouse. Thirty minutes 15 after the "meal," the animals were sacrificed with chloroform. The digestive tract (stomach to colon) was removed. A three gram weight was hung from the colon for 20 seconds. The length of the small intestines and the distance that the "meal" had travelled were measured. 20 Methylcellulose alone and morphine were also evaluated. As can be seen from the following Table I, 5,5-dimethyl-10 - hydroxy - 8 - (3 - methyl-2-octyl)-2-(2-propynyl)-1,2,3,4 - tetrahydro - 5H-[1]benzopyrano[3,4-d]pyridine is more potent than morphine sulfate in slowing intestinal 25 motility in mice. In the table, 5,5-dimethyl-10-hydroxy-8 - (3 - methyl - 2-octyl)-2-(2-propynyl)-1,2,3,4-tetrahydro-5H-[1]benzopyrano[3,4-d]pyridine is designated as A, morphine sulfate as B and methylcellulose as C.

TABLE I

Compound:	Dose, mg./kg.	Time 0', avg. (range)	Time 60', avg. (range)
35	A-----	0.0005	64 (45.1-86.3)
	A-----	0.001	55.3 (31.5-78.8)
	A-----	0.0025	61.2 (42.5-100)
	A-----	0.005	53.7 (43.7-74.7)
	A-----	0.01	55.4 (29.2-88.3)
	A-----	0.1	40.4 (25-54.8)
	A-----	1.0	38.8 (27.7-52.2)
	A-----	10.0	39 (29.5-59.5)
	A-----	100.0	28.2 (17.3-41.7)
	B-----	1	75.5 (46-92)
40	B-----	10	42 (6-69)
	B-----	20	46 (25-79)
	B-----	40	41 (24-95)
	C-----	(1)	72.8 (55-92.7)
			74.6 (59.3-85.4)

¹ 10cc./kg.

Example 2.—Oral effect of 5,5-dimethyl-10-hydroxy-8-(3-methyl - 2 - octyl) - 2-(2-propynyl)-1,2,3,4-tetrahydro-5H - [1]benzopyrano[3,4 - d]pyridine and morphine sulfate on intestinal motility in mice (5 day study)

- 50 Groups of 10 female Swiss-Webster (Wisconsin) mice 16-24 g. were given 0.1 or 1 mg./kg. of 5,5-dimethyl-10-hydroxy - (3 - methoxy-2-octyl)-2-(2-propynyl)-1,2,3,4-tetrahydro - 5H - [1]benzopyrano[3,4 - d]pyridine for 5 days. Similarly, groups of mice were given 1 or 10 mg./kg. of morphine sulfate on the above dosage schedule. The animals were fasted between the 4th and 5th dose of the drugs. On day 5, the drug was administered 0 or 60 minutes prior to a charcoal "meal" (5% Norit charcoal in 0.5% methylcellulose). The "meal" was administered at a volume of 0.25 cc./mouse. Thirty minutes after the "meal," the animals were sacrificed with chloroform. The digestive tract (stomach to colon) was removed and a 3 g. weight was hung from the colon for 20 seconds. The length of the small intestines and the distance that the "meal" had travelled were measured. A control group (10 cc./kg., 0.5% methylcellulose) was dosed in the same manner as the test animals. 5,5-dimethyl - 10 - hydroxy - 8 - (3-methyl-2-octyl)-2-(2-propynyl) - 1,2,3,4 - tetrahydro - 5H - [1]benzopyrano[3,4-d]pyridine was prepared as 0.001 and 0.01% suspensions while morphine sulfate was prepared as 0.01 and

0.01% solutions. Both drugs were in 0.5% methylcellulose. Compounds are designated A, B and C, as in Example 1, in Table II.

TABLE II

Drug:	Dose, mg./kg.	Time 0', avg.	Time 60', avg.
		percent travelled (range)	percent travelled (range)
A-----	0.1	61.5 (36.2-81.8)	74.7 (40-96.3)
A-----	1.0	72.7 (27.3-100)	85 (61.2-100)
B-----	1.0	92 (76.5-100)	95.3 (86.8-100)
C-----	10.0	91 (76-100)	91 (59.6-100)
¹ 10 cc./kg.			

The above data indicate there is some tolerance developed for both 5,5-dimethyl-10-hydroxy-8-(3-methyl-2-octyl) - 2 - (2 - propynyl)-1,2,3,4-tetrahydro-5H-[1] benzopyrano-[3,4-d]pyridine and morphine sulfate when administered for 5 consecutive days; however, there is somewhat less tolerance developed for the compound useful in the practice of this invention than for morphine sulfate.

The compound useful in the practice of this invention can be formulated into various pharmaceutically acceptable dosage forms such as tablets, capsules, pills and the like for immediate or sustained release, by combining

the compound with a suitable pharmaceutically acceptable carrier or diluent according to methods well known in the art. Such dosage forms may additionally include lubricants, excipients, binders, fillers, flavoring and sweetening agents and other therapeutically inert ingredients necessary for the formulation of the desired preparation.

We claim:

1. A method of controlling diarrhea by administering a therapeutically effective amount of 5,5-dimethyl-10-hydroxy - 8 - (3 - methyl-2-octyl)-2-(2-propynyl)-1,2,3,4-tetrahydro - 5H - [1]benzopyrano[3,4-d]pyridine to a patient in need of such treatment.

2. A method in accordance with claim 1 wherein 5,5-dimethyl - 10 - hydroxy - 8-(3 - methyl-2-octyl)-2-(2-propynyl) - 1,2,3,4 - tetrahydro - 5H-[1]benzopyrano-[3,4-d]pyridine is administered in dosages of from 0.005 to 10.0 mg./kg. of body weight daily.

UNITED STATES PATENT OFFICE
CERTIFICATE OF CORRECTION

Patent No. 3,777,028 Dated December 4, 1973

Inventor(s) Louis Selig Harris et al.

It is certified that error appears in the above-identified patent and that said Letters Patent are hereby corrected as shown below:

Column 1, lines 50-60, change the substituent at the right end of the structural formula from " C_6H_{11} " to $--C_5H_{11}--$.

Column 2, line 53, change "hydroxy - (3- methoxy-2-octyl)" to $--hydroxy-8-(3\text{-methoxy-2-octyl})--$.

Signed and sealed this 25th day of June 1974.
